CONTAINER FOR PACKAGING SHEET AND FABRIC MATERIAL

Champe S. Andrews, North Chattanooga, Tenn., assignor to Box Blank Corporation, New York, N. Y., a corporation of Delaware

Application September 19, 1931, Serial No. 563,691

2 Claims. (CL. 206—46)

This invention relates to a container for packaging sheet and fabric material, such as bed spreads, bed covers, carpets, finished materials and cloth.

5 It has been the practice, heretofore, to package such sheets and fabrics by folding the material upon itself and then packaging the same flat in containers. This method of packaging results in a crease along the edges of the material

10 which is very often objectionable. Furthermore when materials are thus packed in flat condition, the containers are often so handled as to place the material on edge which often results in movement and wrinkling of the material in the

15 container. In addition to the wrinkling, the shifting of the fabric against the container walls often times causes injury to the texture of the material. The goods when offered for sale often appear wrinkled, mussed and unattractive.

20 An object of my invention is to provide a method of packaging sheet material in a neat, effective and efficient manner so that when the material is removed therefrom, it is fresh and uncreased, unwrinkled and uninjured.

25 Another object of my invention is to provide a container adapted to effectively package sheet material, which is so constructed that shifting of the material in the container is prevented, and which will generally preserve the material against creasing, wrinkling and injury.

Another object of my invention is to provide a container for packaging sheet material in roll form which is easily and quickly assembled either by hand or machinery, which is strong and durable in construction and attractive and pleasing in appearance.

Although the novel features which are believed to be characteristic of this invention will be particularly pointed out in the claims appended hereto, the invention itself, as to its objects and advantages, and the manner in which it may be carried out, may be better understood by referring to the following description taken in connection with the accompanying drawings forming a part thereof, in which:

Fig. 1 shows my complete container with a roll of sheet material assembled therein, the cover being lifted from the container;

Fig. 2 shows a portion of the barrel of the container in collapsed condition;

Fig. 3 shows a stamped out blank from which the top and bottom covers of my container may be made;

Fig. 4 is a perspective interior view of a fragmentary portion of the cover-forming blank in

the process of being adjusted into cover-forming position;

Fig. 5 is a vertical cross sectional view of a fragmentary portion of my container having a cover of modified construction;

Fig. 6 is a perspective view of my modified cover; and

Fig. 7 is a perspective interior view of my modified cover, certain parts being broken away to more clearly show the construction.

Similar reference characters refer to similar parts throughout the specification and the several views of the drawings.

In the following description and in the claims, various details will be identified by specific names for convenience, but they are intended to be as generic in their application as the art will permit.

My container is preferably made of strong cardboard material and may be shaped so as to most efficiently accommodate the sheet material to be packed therein. I have shown in Fig. 1, an elongated container of octagonal form. The barrel portion 10 of my container is formed from a sheet of card-board material creased as at 11 along spaced lines to form the several side walls of the barrel portion. The vertical edges of the barrel portion may be glued as at 12 or otherwise secured together to form a continuous side wall.

The bottom and top covers preferably telescope over the ends of the barrel portion as shown particularly in Fig. 1. The top and bottom covers may be similarly constructed from a single blank cut to the form shown in Fig. 3. The blank shown in Fig. 3 is scored as at 13 to define the bottom portion 14 of the cover. A plurality of side wall extensions 15 and 16 project outwardly from the scored lines 13 to form the side walls of the cover portion. The side wall extensions 15 are provided with tabs 17 extending laterally from each side of the side wall extension and separated therefrom by scored lines 18. The side wall extensions 16 are without side tabs as will be noted by reference to Fig. 3. The side tabs 17 may be cut to any shape desired from the material provided between adjacent side extensions 15 and 16. Each of said side extensions 15 and 16 is provided with an end flap 19 separated from the extension by a score line 20.

The method of assembling my cover shown in Fig. 3 will now be described. The side extensions 15 and 16 are raised upwardly so that they extend substantially at right angles to the bottom portion 14 of the cover, bending at the creased line 110

13. Side tabs 17 are positioned to rest against the inner face of the adjacent side extension 16, as shown in Fig. 4. The flaps 19 are then turned inwardly and folded against the side tabs 17 and 5 the side extensions 15 and 16. The tabs 17 may be glued or otherwise secured to the inside face of the adjacent side extension 16. The flaps 19 may also be glued or otherwise secured to the inner faces of the side tabs 17 and the inner face of 10 the side extensions 15 and 16. The side extensions 15 and 16 forming the side walls of the cover are thus maintained in permanent upright position.
- A cover of substantially the same construction may be used to close each end of the tubular barrel 15 10. If desired, one of the covers forming the bottom of the tubular container may have comparatively low side walls as shown in Fig. 1 and may be permanently fastened by glue or other means to the tubular barrel.
- 10 20 I have shown in Figs. 6 and 7 a modified cover construction. Referring more particularly to Fig. 7, a band of paper board material is provided which has vertical spaced score lines 21 to define the vertical side portions 22 of the cover. The 25 band may be made continuous by securing the ends thereof together with an adhesive strip, not shown, or other means. A tab 23 is formed integral with each side wall portion 22, but is separated therefrom by a score line 24. Each tab is 30 bent to extend inwardly as shown in Fig. 7 and may be cut out at the corners so as not to interfere with adjacent tabs when in inwardly bent position. The continuous band forming the side portions 22 is placed upon a heavy cardboard blank 25 35 cut to conform to the shape of the side wall portions 22. A sheet of strong and tough paper material 26 is glued over the exterior of the cardboard portion 25 and is provided with tab portions 27 which extend upwardly. Tab portions 27 are 40 adhesively secured to the side wall portions 22, as clearly shown in Fig. 7. A strip 28 of sheet paper material is then adhesively secured around the outside of the side wall portions 22, covering the full height thereof. The upper portion 29 of the 45 strip is folded over the horizontal edge of the side wall portions 22 and adhesively secured to the inside face thereof. To hold the cover completely assembled and give it strength, an inner disc 30 of strong and tough paper material, slightly oversize, is pressed into the cover and seats on the inwardly projecting tab portions 23. The 50 complete cover, thus assembled, is shown in exterior perspective in Fig. 6.
- 55 My novel box as above constructed is especially advantageous in the packaging of bedspreads, bed covers, blankets, carpets, oil cloth, draperies, tapestries, portières and other articles made of fine fabrics. Such sheet materials are packaged in my container in the following manner.
- 60 The sheet material of whatever nature is rolled loosely upon itself to form an elongated roll or cylinder. If the material, is of great width, for example, it may be desirable to fold it over loosely 65 upon itself and then roll it into an elongated roll. In any event the sheet material when so handled is not creased or pressed in any manner. The roll of material is then inserted endwise into the tubular barrel of the container. One of the cover 70 portions may, or may not, be placed upon the end of the tubular barrel before the roll of material is inserted. If it is desired to fix the cover permanently to the barrel after the roll of material has been inserted, it is merely necessary to place a 75 small amount of glue or other adhesive material on

the inside face of the cover and then telescope the cover over the end of the barrel.

As shown in Fig. 1, I may cut an opening 31 in one wall of the barrel portion 10, which serves as a display window, making visible the goods within, without requiring the removal of the goods from the container. A stiff strip of cardboard or other opaque material 32 may be inserted between the goods A and the interior face of the windowed side wall to cover the window and protect the contents during storage and shipping. As clearly shown in Fig. 1, the cardboard 32 is of such width that the side edges thereof seat against the side edges of adjacent side walls, preventing movement or shifting of the cardboard.

When the sheet material is thus packaged, it is always found in fresh condition when removed from the container. The polygonal shape of the barrel lightly engages the roll of material and prevents shifting or movement of the roll within the barrel. The roll of material is thus held in upright position and does not settle and wrinkle within the container even though the container is roughly handled or stood in one position for a long period of time. Furthermore, the barrel is made of limited diameter so that the roll of material presses against all the side walls and the large frictional area thus presented prevents shifting or movement of the roll of material with consequent damage to the texture of the material. 105 My container also presents a sanitary, effective, time saving, and attractive way of packaging roll material in the least possible space.

It is also apparent that by the use of my novel package many different sizes of boxes need not 110 be used. The packaging of bed spreads of various sizes in the usual flat containers, for example, has required boxes in approximately forty different sizes. With my novel container, the manufacturer can cut the barrel portion of the 115 container to the length desired and purchase barrels of say two lengths only. It is not possible to cut off the flat containers now in use, to obtain the various sizes needed. This is an important feature of my invention.

It is understood that I contemplate making my container of square, rectangular, pentagonal, sexagonal, octagonal, or other cross-sectional form as is compassed within the term polygonal.

While certain novel features of the invention 125 have been disclosed and are pointed out in the annexed claims, it will be understood that various omissions, substitutions and changes may be made by those skilled in the art without departing from the spirit of the invention.

What is claimed is:

1. A container for packaging rolls of sheet material made of fine fabrics comprising a body portion of relatively stiff paperboard material in the form of a regular polygonal prism, said body portion being collapsible whereby it may be shipped to the packer in a collapsed condition and cut into the desired roll lengths adapted to receive an elongated roll of material, removable covers adapted to telescope the ends of the body portion, 135 each cover comprising a polygonal shaped cardboard bottom, an annular member of paperboard material provided with score lines defining side wall portions and tabs at the bottom of each side wall, said member resting upon the cardboard bottom with the tabs turned inwardly, a wrap sheet covering the bottom of the cover and provided with tabs adhesively secured to the exterior of the side wall portions, an oversize disc insertable into the open end of said annular member 140 145 150

and adapted to seat on the inturned tabs formed on the side portions and a wrap sheet covering the entire surface of the side walls and adhesively secured thereto.

5 2. A bedspread package, comprising a rolled bedspread enclosed in a container having a body portion of relatively stiff paperboard material in the form of a regular polygonal prism, the outer 10 ply of the bedspread roll being in pressure engaging relation with substantially the entire surface of the inner portion of each face of the prism, whereby relative movement of the roll with respect to the container is prevented, a remov-

able cover member for each end of the body comprising a polygonal shaped bottom portion having a side wall extension projecting radially of the bottom from each edge thereof, means associated with the side wall extensions for maintaining them in the erect position, an unobstructed opening in one of the faces of the prism forming a window in the body of the container through which the contents may be viewed, and an opaque removable shutter for said opening, the shutter being insertable through either end of the container body and held in position by the roll. 85 85
